R. W. GEARHART

REFRIGERATING CABINET

Filed May 22, 1925

UNITED STATES PATENT OFFICE.

RALPH W. GEARHART, OF CLEARFIELD, PENNSYLVANIA, ASSIGNOR TO GEARHART SALES CABINET CO., INC., OF CLEARFIELD, PENNSYLVANIA, A CORPORATION OF DELAWARE.

REFRIGERATING CABINET.

Application filed May 22, 1925. Serial No. 32,065.

In the commercial manufacture of ice cream and other frozen food products, the same are delivered from the freezer in a more or less slushy or semi-solid form, and 5 require hardening before they are adapted for distribution and consumption.

It is for this purpose of hardening that my present invention is more especially intended, but it will be evident to those skilled 10 in the art that my improved cabinet may be employed with great advantage to many other uses involving the refrigeration of food products and other substances.

For this purpose I have invented a cabinet 15 whose walls are insulated against heat and which is provided with internal means for the refrigeration of its interior. The refrigeration may be accomplished by means of pipes mounted within the cabinet and 20 through which a refrigerating agent, such as ammonia or chilled brine is passed, or the cabinet may be provided with a wall tank or tanks through which the chilled brine flows. I prefer to provide the cabinet with hollow 25 walls in which the pipes are coiled, the cavity being water-tight so that the pipes may be immersed in a bath of brine.

A difficulty in the present practice with 30 cabinets of this character is that when the closure is opened to remove a portion of the contents of the cabinet, large quantities of warm air are admitted, thus injuriously affecting the remaining contents of the cabinet and materially raising its interior temperature. Thus, it is impractical to obtain 35 proper hardening or refrigerating results in cases where portions of the contents of the cabinet must be removed or replenished at relatively frequent intervals. The result, in 40 such cases, is that the hardening or refrigeration is only partial or incomplete, and the quality of the goods is seriously impaired.

To overcome this difficulty, I provide in 45 addition to the main door or closure of the cabinet, a plurality of inner closures or doors which close off portions of the interior of the cabinet, so that when a portion of the contents of the cabinet is to be removed, the main door is first opened and then the 50 proper inner closure to gain access to the desired contents, thus avoiding the exposure of the remaining contents to an inrush of warm air. Thus, also, a portion of the contents of the cabinet may be replenished

without exposing the other contents of the 55 cabinet to heating.

In the preferred form of my invention, the interior of the cabinet is provided with a rack upon which the containers, such as flat pans, upon which the articles to be refrigerated are placed, are mounted in tiers, such containers being slidable into and out of said rack through the open door of the cabinet. To enable the cabinet to be readily 60 cleansed at frequent intervals, the rack is arranged to be slid into and out of the cabinet 65 through the opened cabinet door.

The front of the rack is provided with an inner door or closure for each tier, so that when access to a tier is desired, the cabinet 70 door is first opened and then the inner door of the proper tier, the other inner doors remaining closed for the protection of the contents of the other tiers. The inner doors, when all closed, form an inner seal or closure 75 for the cabinet just within the outer door, so that an air space between the inner and outer closures is provided, thus assisting in the insulation of the cabinet against the entrance 80 of heat from without.

My invention consists also in the various subcombinations and details hereinafter described, and also in the construction, and in the arrangement of parts shown.

In the accompanying drawings, Fig. 1 is 85 a perspective view of a cabinet embodying the principles of my invention, the cabinet door being shown open, the rack partially withdrawn from the cabinet and one of the tier doors being partially opened; Fig. 2 is 90 a vertical section of the cabinet taken along the line II-II in Fig. 3; Fig. 3 is a horizontal section of the cabinet taken along the line III-III in Fig. 2; Fig. 4 is an enlarged broken perspective view of the front 95 end of the rack; Fig. 5 is a perspective showing a modified form of rack, and Fig. 6 is an enlarged detail in horizontal section showing a front corner of the cabinet and the rack.

Referring to the drawings, A is the cabinet having an open front. The walls of the cabinet are of heat-insulated character. Thus the outer wall 1 may be wood or metal and within which is a layer of heat-insulating 105 material 2, such as cork. The inner wall is preferably of metal and in the form of a metal tank 3 which extends from the floor

to the top of the cabinet and runs around the three sides of the same. At the front of the cabinet, the door opening is defined at either side by a post 4, which may be of wood. The top of the cabinet may be removable, such as the lid B. The top, whether in the form of a removable lid or a permanently attached closure, is preferably provided with an interlining of cork or other heat-insulating material, as is likewise the bottom or floor of the cabinet.

The front of the cabinet is closed by an outer door C, which is interlined with heat insulating material, as shown in Fig. 5, and which door is preferably hinged to swing on a vertical axis.

E represents a continuous pipe which is coiled in the tank 3 in horizontal lengths connected at the ends by the vertical legs 5. 20 The upper end of the pipe is led out, as shown at 6 in Figs. 1 and 2 through the side of the cabinet, while the lower end 7 is extended vertically and also led out through the side of the cabinet. Ammonia gas, refrigerated brine or some other suitable refrigerating agent is caused to pass through said pipe. I also prefer to maintain in said tank a bath of brine which is chilled by the contents of the pipe, or the brine contents 25 of the tank may be replaced with freshly chilled brine at intervals, as may be desired.

D is a rack, Figs. 1, 2, 3, 4 and 6, which, in the embodiment shown, is composed of vertical front legs 8 which are shown as 30 angle irons with their flanges at the front and turned out to either side, as shown in Figs. 3, 4 and 6. The rear legs 9 are also angle irons, turned as shown in Fig. 3. The horizontal members or supports 10 of the 35 rack are angle irons with their horizontal flanges below and turned inwardly, as shown. These horizontal members are attached to legs 8 and 9 at their ends, and are also intermediate of their ends provided with the vertical stiffening bars 11, of flat metal, 40 attached to their outer faces. At the tops and bottoms, the front legs are connected and held in proper spaced relation by cross-struts 12. Similar cross-struts are provided 45 for the rear legs 9.

The horizontal members form a plurality of tiers for the storage of substances on the rack, the substances to be refrigerated being 50 placed on long shallow pans 13 which may be slid into the rack from the front, being supported by the inturned flanges of the horizontal members 10.

The rack is of proper width, so that when 55 it is slid into the cabinet, the out-turned flanges of the front legs 8 bear against the outer surfaces of the posts 4, as shown in Figs. 3 and 6, thus closing the front of the cabinet at each side of the rack against the entrance of air.

60 14 represents the inner doors, which are

preferably of sheet metal and are pivotally attached by their top edges to the front of the rack, one for each tier. Thus said doors may be provided at their tops with horizontal pivot shafts 15 whose ends are journaled in socket holes in the front legs 8. It is evident that when one of said inner or tier-doors is raised, a pan may be inserted into or withdrawn from the rack, without disturbing the other doors, and thus the material admission of warm air is prevented. It is also evident that when all the inner doors are closed, an inner-seal or closure for the cabinet doorway is provided.

In Fig. 5 I illustrate a modified form of 70 rack D' wherein the sides and rear end and also, if preferred the top and bottom are enclosed, the horizontally disposed angle irons 10^a being attached to the side walls for the support of the pans 13. The front of the rack D' is provided with the angle-iron members 8^a, disposed like the members 8 of the rack D so as to fit against the door posts 4 and close the sides of the rack against the entrance of the air. The lowest tier of the 75 rack D' is shown provided with a continuous floor 10^b as a substitute for the angle irons 10^a. By providing a tight floor for each tier I completely close it off from the other tiers, so that the entrance of warm air 80 into a tier is absolutely prevented unless its individual door is opened. In Fig. 5 for the sake of clearness only one of the inner doors 14 are shown in place.

Thus the cabinet may be loaded by tiers 100 without seriously raising its internal temperature, and the contents of individual tiers may be removed or replenished in like manner.

I am thus able to progressively and effectively harden the contents of any one or more tiers, regardless of the fact that the contents of another tier or tiers have been 105 repeatedly disturbed.

What I desire to claim is:—

1. In a refrigerating cabinet provided with cooling means, the combination of an outer casing having a door-way provided with a door, a rack within said outer casing and provided with a plurality of horizontal slideways each adapted to receive a container, and an individual door for the front end of each of said slideways, said door being arranged to close to form a tight closure for the outer end of the slideway after 115 the container has been inserted into the slideway.

2. In a refrigerating cabinet provided with cooling means, the combination of an outer casing having a door-way provided with a door, a rack within said outer casing and provided with a plurality of horizontal slideways each adapted to receive a container, and an individual door for the front 125 end of each of said slideways, said door be- 120

ing arranged to close to form a tight closure for the outer end of the slideway after the container has been inserted into the slideway, and said individual doors being also arranged when all closed to form an inner seal for the door-way of the outer casing.

3. In a refrigerating cabinet provided with cooling means, the combination of an outer casing having a door-way provided with a door, a rack within said casing, the front end of said rack being arranged to fit the door-way to seal the same against the entrance of air along the sides of the rack, and said rack being provided with a plurality of slideways each adapted to receive a container, and an individual door for the front end of each slideway arranged to close to form a tight closure for the outer end of the slideway after the container has been inserted into the slideway.

4. In a refrigerating cabinet, the combination of an outer casing having a door-way in its front provided with a door, pipe coils arranged against the inner surfaces of the side and rear walls of the casing for the passage therethrough of a refrigerating agent, a rack in said casing surrounded at its sides and rear by said coils, said rack fitting at the front of said door-way and

said rack being provided with slideways adapted to receive containers inserted through said door-way, and an individual drop door mounted on said rack at the front of each slideway, said door being arranged to drop down and close the outer end of the slideway after the container is inserted or withdrawn.

5. In a refrigerating cabinet, the combination of an outer casing having a door-way in its front provided with a door, pipe coils arranged against the inner surfaces of the side and rear walls of the casing for the passage therethrough of a refrigerating agent, a rack in said casing surrounded at its sides and rear by said coils, said rack fitting at the front in said door-way and said rack being provided with slideways adapted to receive containers inserted through said door-way, and an individual drop door mounted on said rack at the front of each slideway, said door being arranged to drop down and close the outer end of the slideway after the container is inserted or withdrawn, and said drop doors being also arranged when they are all closed to form an inner seal for said door-way.

Signed at Clearfield, Pa., this 25th day of April 1925.

RALPH W. GEARHART.
